UNITED STATES PATENT OFFICE.

HENRI GABRIEL EDOUARD AGIER, OF NEW YORK, N. Y.

BLOCK-PRINTING MACHINE FOR FABRICS.

1,384,934.

Specification of Letters Patent. Patented July 19, 1921.

Application filed October 23, 1920. Serial No. 418,996.

To all whom it may concern:

Be it known that I, HENRI GABRIEL EDOUARD AGIER, a citizen of the United States, residing at New York, in the county of New York and State of New York, have invented certain new and useful Improvements in Block-Printing Machines for Fabrics; and I do hereby declare the following to be a full, clear, and exact description of the invention, such as will enable others skilled in the art to which it appertains to make and use the same.

The object of the invention is to provide simple and efficient mechanism for accomplishing the systematic and uniform printing of fabric under conditions minimizing the factor of uncertainty in the application of the printing blocks, to the surface of the fabric and hence the loss incident thereto, the element of uncertainty in the ordinary practice frequently resulting in the doubling or overlapping of the impressions of the pattern or the failure to secure accurate registration or matching thereof; and with this and related objects in view, the invention consists in a construction and combination of parts of which a preferred embodiment is shown in the drawings, wherein—

30 Figure 1 is a front view of an apparatus with the parts shown in the printing position in full lines, and indicating in dotted lines an intermediate and the upper terminal positions of the follower or carrier.

35 Fig. 2 is a side view showing the follower in its depressed position with the block carrying head in the color applying or operative position.

Fig. 3 is a vertical sectional view taken in a plane parallel with the front of the machine.

Fig. 4 is a horizontal section on the plane indicated by the line 4—4 of Fig. 1.

Fig. 5 is a detail view of the follower detached.

Fig. 6 is a detail section on the line 6—6 of Fig. 2.

Fig. 7 is a detail view of the fabric feed mechanism for periodically advancing the fabric from the stock or supply roll or drum to the receiving or storage roll or drum.

Fig. 8 is a detail section on the line 8—8 of Fig. 1.

55 Fig. 9 is a detail end view, partly in section, of the stock or supply roll support.

The apparatus consists essentially of an upright guide frame 10 in which is mounted for vertical reciprocatory movement a follower or carrier 11 supporting an oscillatory head 12 to which is attached a printing or pattern block 13; together with means for actuating the follower or carrier, means for applying color to the printing or pattern block, and means for intermittently feeding the fabric through prescribed longitudinal distances, to present fresh surfaces thereof to receive the impressions of the printing or pattern block.

The oscillatory head is fulcrumed at 14 upon the follower or carrier and is provided with extension arms 15 connected by a transverse traveler rod 16 designed to operate in a cam guide 17, so that, as the follower or carrier is vertically reciprocated by means hereinafter described, an oscillatory movement is imparted to the head to alternately present the printing or pattern block on the face thereof in parallelism with the table 18 for impressing the fabric extended upon said table, and applying said printing block or face to the color distributing means indicated generally at 19, said positions of the head being indicated respectively in full and dotted lines in Fig. 1.

In the construction illustrated the guide 17 is provided with the parallel vertical runs 17^a and 17^b connected by a curved or arcuate run 17^c so that as the follower or carrier is moved upward in the guide frame, the head 12 is first raised with its printing or pattern face in a horizontal position from the surface of the fabric, and is then turned toward the side of the frame and conducted upward with the printing face in a substantially vertical position as indicated in dotted lines in Fig. 1, to traverse the color distributing rolls 20 of which a series may be employed as shown in the drawing, arranged with their surfaces in contact as shown in Fig. 3 and receiving color from a belt or apron 21 which traverses the uppermost or feed roll 22 and extends downward into a font 23 containing the coloring material in a liquid form. The lower end of the belt 105 extends around a direction roll 24 or any equivalent thereof.

The fabric to be printed, which is indicated at 25, is carried by a stock or supply roll or drum 26 and a receiving or storage roll or drum 27, and intermediately, in addition to traversing the printing table 18,

traverses a feed roll 28 and direction rolls 29 of which any desired number may be employed, those direction rolls which are located between the table and the storage or receiving roll preferably being arranged at such intervals as to provide for an exposure of the fabric for a sufficient distance and time, according to the speed of operation of the machine, to permit of the drying 10 of the color before the fabric is wound upon the storage roll or drum.

The drive shaft 30 of the machine may receive motion from a motor 31 or any equivalent source of power through a belt 15 traversing a pulley 33 and may be provided with a crank 34 connected by pitmen 32 with the follower or carrier, so that the indicated reciprocatory movement may be imparted to the latter to cause the oscillatory 20 movement of the head to alternately impress the fabric and receive a fresh supply of color from the color distributing means.

In order to secure the periodic or step-by-step movement of the fabric through predetermined and uniform distances in timed 25 relation with the reciprocatory movements of the follower or carrier and hence of the printing head, the storage or receiving drum or roll 27 may be provided with any suitable 30 compensating take-up serving to maintain a uniform tension upon the fabric and reel the same as it is loosened, no specific illustration of such means being deemed necessary in this connection as the same may be of any 35 preferred or approved form, and the feed roll or drum 28 is provided with feed mechanism consisting, for example and as illustrated in the drawings, particularly in Figs. 1 and 7, of a reciprocatory rack bar 36 engaged 40 with a pinion 37 and carrying a pawl 38 engaging a ratchet 39, said rack bar receiving motion at intervals through an oscillatory arm 40 actuated by a cam 41. The spindle 42 of the cam may be connected by 45 a train of gears 43 with the drive shaft 30 so as to receive a continuous rotary movement, and the cam operates upon the oscillatory arm 40 at intervals to cause the movement of the rack to advance the pinion and 50 thus through the ratchet mechanism turn the feed roll a prescribed distance to draw the fabric from the stock or supply roll or drum and permit it to be taken up by the storage or receiving drum, such advance 55 movement of the fabric being effected in the intervals between the periods of impression of the printing or pattern block.

Having thus described the invention, what I claim is:

60 1. A fabric printing machine having a vertical guide frame, a follower or carrier reciprocably mounted in said frame, a tilting head fulcrumed for oscillatory movement upon the follower or carrier and carrying a printing block, color distributing

means located at one side of the path of movement of the follower or carrier, supply and receiving drums for the fabric, and means for maintaining a prescribed area of the fabric in the path of movement of the 70 printing block.

2. A fabric printing machine having an upright guide frame, a follower or carrier reciprocably mounted in said frame, a tilting head fulcrumed upon the follower or carrier for supporting a printing block, means for tilting the head as it recedes from its printing position to dispose the face of the printing block in substantial parallelism with its path of movement, color distributing 80 rolls located at one side of the path of the carrier or follower, for contact with the face of the printing block, and means for carrying and presenting the fabric in the path of movement of the printing block. 85

3. A fabric printing machine having a guide frame, a follower or carrier reciprocably mounted in the frame, a tilting head fulcrumed upon and supported by the follower or carrier and provided with a printing block or face, means for tilting said head as the follower or carrier recedes from the printing position to dispose the printing block or face in substantial parallelism with the path of movement of the follower or 90 carrier, and color distributing means arranged at one side of and parallel with the path of movement of the follower or carrier for traverse by said printing block or face. 95

4. A fabric printing machine having a 100 guide frame, a follower or carrier reciprocably mounted in the frame, a tilting head fulcrumed upon and supported by the follower or carrier and provided with a printing block or face, means for tilting said head 105 as the follower or carrier recedes from the printing position to dispose the printing block or face in substantial parallelism with the path of movement of the follower or carrier, and color distributing means arranged at one side of and parallel with the path of movement of the follower or carrier for traverse by said printing block or face, 110 said means consisting of a series of transverse superficially contacting distributing 115 rolls, and means for applying color to one of said rolls.

5. A fabric printing machine having a guide frame, a follower or carrier reciprocably mounted in the frame, a tilting head 120 fulcrumed upon and supported by the follower or carrier and provided with a printing block or face, means for tilting said head as the follower or carrier recedes from the printing position to dispose the printing 125 block or face in substantial parallelism with the path of movement of the follower or carrier, and color distributing means arranged at one side of and parallel with the path of movement of the follower or carrier 130

- for traverse by said printing block or face, said means consisting of a series of transverse superficially contacting superposed distributing rolls, mutually arranged for 5 contact with the printing face or block, and means for applying color to the uppermost roll of said series.
6. A fabric printing machine having a guide frame, a follower or carrier reciprocally mounted in the frame, a tilting head fulcrumed upon and supported by the follower or carrier and provided with a printing block or face, means for tilting said head as the follower or carrier recedes from 10 the printing position to dispose the printing block or face in substantial parallelism with the path of movement of the follower or carrier, and color distributing means arranged at one side of and parallel with the 15 path of movement of the follower or carrier for traverse by said printing block or face, said means consisting of a series of transverse superficially contacting superposed distributing rolls mutually arranged 20 for contact with the surface of the printing block or face, a color font, and an endless color carrying apron extending through the font and traversing the uppermost roll 25 of said series.
7. A fabric printing machine having a 30 guide frame and a printing table arranged in transverse relation to the guide frame,

supply and receiving rolls or drums for fabric to traverse said table, feed mechanism for imparting a step-by-step forward movement through prescribed distances to the fabric, a follower or carrier reciprocably mounted in said frame for movement toward and from the plane of the table, a tilting head fulcrumed upon said follower or carrier and provided with a printing block of which the printing face is adapted for contact with the surface of fabric arranged upon said table, means for imparting reciprocal movement to said follower or 40 carrier, in timed relation with the operation of the fabric feed mechanism, means for tilting said head as the follower or carrier recedes from the table, to dispose the printing face in substantial parallelism with the 45 path of movement of the follower or carrier, and color distributing means disposed at one side of the path of the follower or carrier for traverse by the printing face of the head during the movement of the follower 50 or carrier from and toward the plane of said table.

In testimony whereof I affix my signature in presence of two witnesses.
